AERIAL NAVIGATION MACHINE UTILIZING
A LIGHT GAS

Etienne Edmond Oehmichen, Valentigney, France

Application March 15, 1932, Serial No. 599,038
In France March 17, 1931

1 Claim. (Cl. 244—6)

I have filed an application in France on March 17th, 1931.

The present invention relates to an aerial navigation machine of special construction and of a combined system, that is to say, that its ascending force is due simultaneously to the aerostatic lift of the air and to the aerodynamic actions of the sustaining propellers. The principles of the present invention, which have been established to a great extent in accordance with 10 the experience and personal experiments of the inventor, are explained hereafter:

An elongated balloon, for example, of only 400 cubic meters has a radius of action of practically 15 zero, for it can hardly carry the weight of one passenger and that of the machine and attain a speed of approximately 50 kilometers per hour.

The said sustaining systems will be capable of developing a carrying capacity, the average of which varies from 6 to 7 kilos per horse power.

The machine in question fitted out with such a sustaining system will therefore be capable of raising an additional load, besides the material already loaded, which additional load may vary 25 from 3 to 6 kilos for each horse power supplied by the sustaining engine. Supposing that the number of horse power of the said engine is P, the machine will then be capable of carrying a load of fuel equal to at least 3 P. Consequently, 30 the same will have a much larger radius of action. Under these conditions the balloon of 400 cubic metres, which we have considered, supplied with a sustaining system of 40 horse power, will increase its radius of action from 0 to 350 kilo- 35 metres.

On the other hand it is not necessary to employ a supplementary motor for actuating the sustaining system, but use may be made of the same motor of the flying machine, thus increasing 40 the radius of action in a still more considerable manner.

The sustaining propellers may be of the ordinary type with vertical axes or inclined ones.

On account of the translation the ordinary 45 sustaining propellers will be enabled to increase their sustaining qualities in a very efficient manner. The composing parts will be dimensioned in such a manner that the start with full load does not require the whole power of the motor 50 for the sustentation but on the contrary a portion of this power will be disposable to actuate the driving propeller. As the speed of the sustaining propellers increases at the same time the horizontal speed of the whole machine grows, it 55 will be possible to diminish considerably the in-

cidence of the sustaining propellers and consequently to liberate an important quantity of power, which the driving propeller will utilize in an efficient manner.

The inclined propellers are more advantageous 60 since they permit to obtain horizontal driving efficiencies which are equal to those supplied by an ordinary propeller disposed in normal manner besides giving the benefit of a very important component of translation.

Under these latter conditions an aerial navigation machine of 400 cubic metres, as considered previously, supplied with sustaining propellers of about 20° inclination and fitted out with an engine of 40 horse power driving the said 65 propellers and at the same time having a supplementary horizontal driving propeller of variable 70 and reversible pitch, will reach and even surpass a radius of action of 1000 kilometres.

However, it may be mentioned now, that the 75 machine has changed its character entirely and has become a machine of the heavier-than-air type.

Consequently, if, on account of an accident to the mechanism, the sustaining effort developed 80 mechanically fails, the machine will tend to drop. It is, therefore, indispensable either to avoid this fall or to reduce the speed of the fall sufficiently so as to ensure a safe landing without accident.

One way, for instance, to reduce the speed of the 85 fall consists in releasing the machine instantaneously by unloading as rapidly as possible the load of fuel, which is of considerable weight. Further to release all heavy articles, which can be spared without causing inconvenience, should be 90 considered. The descending speed must be limited to a value, which the inventor through his personal experiments has found to be of a maximum of 5 metres per second, because, when once it exceeds this limit, even with landing devices of long course, the regaining of contact with the 95 ground will generally damage the machine. If the release is insufficient to limit the fall to a speed inferior to 5 metres, the machine must moreover be so arranged as to offer a certain resistance to the air during the said fall.

It is known that the resistance to the advancement of a balloon in the air is generally very weak. This resistance which we shall call longitudinal 105 resistance and which is generally reported to be of a speed of 10 metres per second, is of an average of 1/50 but may amount to 1/100 of the transversal resistance or the resistance which the envelope offers to a translating movement, which takes place at the same speed but in a direction 110

perpendicular to the longitudinal axis of the balloon.

For instance, an elongated balloon of 21 metres in length and of a midship diameter of 6 metres provided with its featherings develops in translation movement perpendicular to its longitudinal axis a resistance of 140 kilos at the speed of 5 metres per second and by suitable means, such as collars or longitudinal braking surfaces of very weak development, this resistance may under the same conditions reach 230 kilos. Thus, in a horizontal projection with equal surface, there may be obtained a resistance of equal value with that of any of the best parachutes.

15 All these principles being thus established, the invention has for its object the combination of an aerial navigation machine of small volume with a driving machine actuating one or more propellers, which are capable of developing at the same time sustaining efforts as well as horizontal driving efforts, the said combination being chiefly characterized as follows:

The total ascending force, that is to say, the lift of the air on the whole machine, which is not sufficient to raise the machine, is comprised between two limits.

25 The lower limit (this lower limit being quite rigorous in the present case) of the ascending power or aerostatic lift of the air on whole, the machine is equal to the weight of the machine as described previously (envelope, gas, accessories, engine, passengers, armament etc.) not including the fuel and furthermore diminished by the transversal resistance opposed by the machine during a uniform descent of 5 metres per second in calm air.

30 When the ascending force is in the proximity of the upper limit or for some important reason surpasses the same and if the sustaining engine stops, it will be sufficient to release the whole or a portion of the fuel in order to keep the aerial navigation machine in the air.

35 On the contrary, when the ascending force is close to the lower limit and if the engine stops even after evacuating all the fuel which is disposable, then the descent will obviously take place, without exceeding, however, the speed of 5 metres per second, which is just the speed allowing a landing without accident, providing of course, that the landing device is suitably arranged.

40 The upper limit described previously cannot be surpassed to a very great extent, as then the efficiency of the machine would be reduced to such extent as to be without any interest. Obviously, the aerial navigation machine deprived of its engine has no other way than to land within a more or less limited space of time, especially when the balloon in question is a flexible one.

45 Let us consider the different cases by taking for example, an aerial navigation machine carrying 500 kilos of fuel, the total weight of which, without comprising the fuel, that is to say, envelope, gas, passengers, engine, armament etc., being equal to 1000 kilos.

50 When descending vertically at the speed of 5 metres per second let us presume that the resistance opposed by the aerial navigation machine is equal to 250 kilos. Thus fixing the resistance beforehand, for the same depends on the capacity of the envelope, it will enable us to deduce the volume therefrom and then determine the latter through successive approximations.

55 This being stated, the lower limit of the gross ascending force (that is to say, the lift of the air on the machine without any subtraction) should be 1000—250 equal to 750 kilos, which cor-

responds to a volume of little more than 560 cubic metres, which is exceedingly reduced with regard to the comparatively big load of fuel provision, which is of 500 kilos.

At the start the machine is slightly heavier than the air, the surplus of weight being 250+500 (fuel) equal to 750 kilos.

On the contrary, consider an ascending force equal to the upper limit fixed previously, that is to say, a gross ascending force (lift of the air on the machine without any subtraction) equal to the total weight without fuel amounting to 1000 kilos. This corresponds to a volume of the envelope of little less than 800 cubic meters. The machine will still be slightly heavier than the air and at the start the surplus of weight is only the one of the fuel provision amounting to 500 kilos.

Now, considering an ascending force surpassing the upper limit by the quantity stated before, that is to say, 250 kilos, half of the weight of the fuel provision. The lift of the air on the envelope without any subtraction will be of 1250 kilos, which corresponds to a volume of the envelope of little less than 1000 cubic metres.

100 The machine carrying its fuel is still slightly heavier than the air, the excess of the weight at the start being of 250 kilos. But in this third case, as soon as half of the fuel is consumed, at this moment the machine then becomes lighter than the air and in case of failure of the mechanism, will not drop.

105 However, the fact should be noted, that the before-mentioned third case is not of great practical interest. It should only be considered in the case of journeys above regions where the descent cannot be effected and especially, when multiple engines are employed, permitting to continue the route by keeping only a small portion of the fuel and after having released the surplus of the fuel, in case of a total or partial failure of the engines.

110 If the engines are of the multiple type it is advantageous to divide the tanks into as many compartments as there are engines, so that, if one of the engines fail definitely, the contents of only one of the compartments may be released.

115 Furthermore, if the stop of an engine can be considered as temporary and is likely to be repaired, it will not be necessary to empty the corresponding tank immediately, but it will suffice to increase the action of the other engine or engines during such time of the repair.

120 The auxiliary devices likely to increase the transversal resistance of the envelope may be of any suitable type. Single collars surrounding the envelope will be chosen, which, for instance, unfold at the moment of descent, whilst parachutes placed on top of the envelope, which during the descent, will unfold equally as explained hereafter.

In the drawing:

125 Fig. 1 shows a diagrammatic view of the whole aerial navigation machine.

130 Fig. 2 shows a diagrammatic detail of the use of the auxiliar devices for braking of descent and

135 Fig. 3 shows a rear view corresponding to Fig. 2.

140 Referring to Fig. 1 the aerial navigation machine consists of an envelope 1, a chassis 2, a set of inclined sustaining propellers 3, propellers 4, of variable and reversible pitch working horizontally, tanks 5, which may be emptied instantaneously and even eventually be detached from

the body of the aerial navigation machine; as shown they are disposed on the vertical of the centre of gravity G. 6 represents the sole engine and 7 the landing device. 8 represents the 5 anchoring system with the harpoon projected by means of carbonic gas with its rope and the emptying device as described in the French patent specification filed by the same inventor on February 6th, 1930, (P. V. 289,514).

10 Figs. 2 and 3 show the arrangement of the collars around the envelope, as it is already known and applied to spherical balloons. Therefore, this arrangement is not claimed by the present invention and only given by way of example as to the 15 means for increasing the transversal resistance to the descent.

A collar *ab* is arranged around the envelope and, due to the displacing of the machine, remains normally flat against the said envelope, 20 unfolding only during the descent. Such a collar attached to the envelope like a bandrol following the line *c*, contributes to a great extent to increase the transversal resistance of the envelope. The ends of the bandrols *ab* are retained by small 25 ropes *d*, so that under the influence of the wind produced by the descent, the said bandrols, which surround the envelope, tend to unfold, without being capable of turning completely towards the top.

30 It should, however, be noted that it may be possible, due to the expansion of the envelope, to provide entirely opened parachutes on top of it, which may be separated from the envelope by the wind of descent.

35 Nevertheless, as, due to the backwind which follows the said envelope during its descent, the unfolding of such parachutes covering, for instance, the upper surface of the envelope, presents certain difficulties, it is indispensable to make use 40 of projection devices, which are to separate the parachute from the envelope. This will be easily attained by providing a tube *f* ending at the centre of the parachute and communicating with a gas tank *g*, containing, for instance, carbonic acid under pressure.

45 When the gas enters the tube, the parachute will be inflated and is kept off sufficiently from the envelope, so that the wind on the descent may complete the unfolding at *e'* (Figs. 2 and 3).

If the parachute covers the valve *h*, the same 50 result is obtained by letting escape a certain quantity of gas through the valve, which will raise the parachute sufficiently so as to allow its removal from the envelope.

55 The retaining ropes of the parachute should normally terminate at a central fastening system *j*, which in ordinary service maintains the parachute flat against the envelope and releases it only when necessary, in this case releasing the 60 small ropes all at the same time.

This arrangement, which in itself is not fundamental, is only given by way of example for means which may be employed in order to increase the transversal resistance of the envelope and concerns the object of the invention only indirectly. 65 In fact, many other arrangements may be real-

ized and they only differ between themselves by their different efficiency and their more or less difficult facility of use.

It is to be stated that the tanks should be mounted so as to be centred at the centre of gravity G or arranged in such a manner, so that their emptying does not unbalance the machine. 80

It does not matter what kind of rapidly working emptying device is employed. The simplest ones consist of a valve 9 with a big opening sustained by a belt, which can be operated at any moment by the pilot. 85

Obviously, it must be understood that the load so far described as fuel may be composed differently and include a certain part of non combustible materials destined only for projection. 90

This applies, for instance, to a water tank and articles, which one can get rid of at any moment, such as uncharged bombs, instruments of no prime importance for the navigation, a wireless set, different impediments which one can easily release and which can be taken in account when calculating the weights at the start. 95

The machine must also be provided with a landing device representing on the ground a polygon of sustentation sufficient to ensure the stability of the machine on the ground. Means of anchoring should be considered on the bow, thus to allow the landing on an open field and to avoid the dragging. It may be of some interest 105 to utilize the means as mentioned in the French patent specification filed by the same inventor on the 6th February, 1930, Patent No. 705,665.

As explained previously, the machine is slightly heavier than the air and therefore it must be 110 provided with landing accommodations which are employed in such kind of aerial navigation machines.

If the whole machine does not differ substantially from a combined machine, it may be noted 115 that the principle of the present invention consists of a determined combination of weights, transversal resistances of determined power and consequently of efforts of mechanical convenience as well as of the volume of the machine. All this 120 permits to obtain with the same volume of gas provided a considerable increase of the speed of the machine and of its radius of action, ensuring at the same time sufficient working safety. 125

What I claim is:

An aerial machine comprising an elongated envelope, a chassis depending therefrom, a propeller journaled to the rear end of the chassis for rotation about an axis parallel with the longitudinal axis of the envelope, a second propeller journaled 130 upon the chassis for rotation about an axis inclined upwardly toward the center of the envelope, the last said propeller and the axis thereof being located between the first mentioned propeller and a vertical plane passing through the 135 envelope at a point midway between the ends thereof and a bandrol collar carried at the lower portion of the envelope and disposed over and spaced from the second mentioned propeller and adapted to receive a blast of air therefrom. 140

ETIENNE EDMOND OEHMICHEN.
